FIRE EXTINGUISHER CHARGE

Application filed June 17, 1929. Serial No. 371,378.

This invention relates to fire extinguishers, and particularly to charges for fire extinguishers of the chemical reaction type.

One of the principal objects of this invention is to provide a charge for fire extinguishers of this type which will withstand extremely low temperatures without freezing, and which will react with high efficiency at such extremely low temperatures.

Other objects and advantages of the invention will be apparent from the following description, the accompanying drawing and appended claims.

In the drawing in which like characters of reference designate like parts throughout the several views thereof,

Fig. 1 is a central vertical sectional view through an extinguisher adapted to receive a charge of this invention;

Fig. 2 is a fragmentary vertical sectional view through a modified form of inner tube for the extinguisher of Fig. 1; and

Fig. 3 is a plan view looking upwardly upon the bottom of Fig. 2.

Of the chemical reaction type of extinguishers, that generally known as the soda and acid extinguisher is typical. One principal objection to an extinguisher of the soda and acid type, containing a solution such as a water solution of sodium bicarbonate, is that the solution will freeze at temperatures not much below the freezing point of water. Not only does the bicarbonate solution freeze at low temperatures ordinarily encountered in temperate and cold climates, but furthermore the chemical reagents of the charge become so sluggish at low temperatures that the extinguisher becomes practically inoperative as far as effective fire extinguisher use is concerned.

In accordance with the present invention, a fire extinguisher charge is provided in which the various constituents or separate portions thereof will withstand temperatures as low as -40° C . without freezing, and the gas generating portions will react with high efficiency at such extremely low temperatures. This is of peculiar importance because Underwriters' Laboratories require this perform-

ance of an extinguisher in order to receive a preferred rating.

I have discovered that a gas forming material, such as sodium bicarbonate, mixed with a metal, such as magnesium, will react with high efficiency with an acid liquid, such as hydrochloric acid, at extremely low temperatures of the order above mentioned. Better results are secured when the metal is finely divided, powdered magnesium being very satisfactory. The reaction of such a metal with an acid, such as hydrochloric acid, is highly exothermic, generating considerable heat and warming up the other materials of the charge to such a temperature that an efficient and effective reaction takes place between the acid and the carbonate bearing material. The entire reaction takes place quite rapidly so that a proper building up of gas pressure upon operation of the extinguisher is insured even at an extremely low temperature of the order of -40° C .

While I prefer to use powdered magnesium, other metals such as sodium or potassium will also function in this manner. However, the reaction is more difficult to control with metals of the alkali group due to the violence of their reaction. Powdered magnesium on the other hand when used in the proper proportions gives a vigorous but readily controlled reaction with the acid liquid. Any suitable acid or acid salt which in solution will react with the metal may be used, but preferably a liquid which is non-freezing at such extremely low temperatures is used. Hydrochloric acid of a concentration of about 20% to 25% satisfies this requirement. Other commonly used acids, such as sulphuric acid of the proper concentration, may be used. Any suitable carbonate material, such as bicarbonate or a normal carbonate, is satisfactory.

The carbonate bearing material is preferably used in the solid state, and the finely divided metal may be mixed directly with the carbonate salt. The carbonate portion of the charge being present in the solid state is of course not subject to freezing, and an acid of the proper concentration will also withstand freezing at low temperatures of 100° F .

the order mentioned. With the gas generating charge is preferably used a fire extinguishing liquid which constitutes a third normally separated portion of the extinguisher charge. Any suitable non-freezing liquid may be used, such as a water solution of calcium chloride, carbon tetrachloride, carbon tetrachloride mixed with chloroform, or a water solution of ethylene glycol.

Suitable extinguisher construction adapted to receive a three portion charge may be used. Referring to the drawing, there is shown therein a satisfactory extinguisher construction adapted to receive and operate upon the charge of this invention. This extinguisher comprises a sheet metal outer container 10 having a downwardly extending flange portion 11 forming a base upon which the extinguisher may sit in upright position. The lower end of the container is closed by a sheet metal bottom 12 which is attached to the inner wall of the shell in any suitable manner as by soldering. The top of the shell is provided with a centrally arranged opening which receives therein a cover casting 13 having a filling opening 14, and provided with an externally screw threaded portion 15 adapted to receive thereon a cover 16. The cover 16 carries a suitable handle 17, which as shown is in the form of a ring to serve as a base upon which the extinguisher is adapted to rest when inverted. An annular washer 17 is positioned between the cover 16 and the upper end of the cover casting 13.

Adjacent the upper end of the extinguisher and passing through the wall of the shell is a discharge casting 20. This casting is provided with an enlarged shoulder 21 soldered to the shell to which is secured a screen 22 by an inturned lip 23. The outer end of the casting 20 is provided with a threaded nipple which receives the usual flexible hose carrying a discharge nozzle 26.

Supported within the outer container 10 is a normally closed sheet metal tube 30 provided at its upper end with external screw threads adapted to be received by internal screw threads carried by the cover 16. The tube 30 is of slightly smaller diameter than the diameter of the filling opening 14 so that the tube 30 and mechanism carried thereby may be inserted or withdrawn as a unit with the cover 16. Extending through an opening 34 in the bottom of the tube 30 and soldered thereto is a supporting member or rod 35, to the upper end of which is attached a cup shaped member 37 carrying a cushioning seat 38 of cork or other resilient material. Resting upon the seat 38 is the mouth of an acid bottle 41, the neck of the bottle being closed by a stop 42. Resting upon the upper end of the bottle 41 is a second container 44 adapted to receive the proper quantity of mixed carbonate bearing salt and finely divided metal. As is clearly evident from Fig.

1 of the drawing, a comparatively small container 44 suffices to hold the solid mixed carbonate-metal portion of the charge. The usual quantity of carbonate in proportion to the quantity of acid may be employed as in the conventional charges of soda-acid extinguishers in order to develop the customary expelling gas pressure. The amount of powdered metal in proportion to the carbonate may be varied over wide limits, it being only 75 desirable that sufficient metal be provided to generate heat by the exothermic reaction sufficient to heat up the carbonate and acid portion of the charge when mixed from the low 80 sub-freezing temperature to a temperature above the freezing point of water, or to a reactive temperature as previously described. This may be easily determined from the known exothermic reaction of the powdered metal and acid, and the known specific heats 85 of the carbonate and acid for the temperature rise desired. In the interests of economy, it is desirable that only a small proportion of metal be used such as to give this required temperature rise, but the charge is fully operative over a wide range of proportions considerably in excess of this. As an example of a charge in accordance with this invention for a 2½ gallon extinguisher, the following is mentioned as giving very satisfactory results:—

5.3 ounces dry sodium bicarbonate
.4 ounces finely powdered magnesium
11.5 ounces hydrochloric acid of about 22%
strength

100

The upper end of the container 44 is closed by a stopper 45. When an acid, such as hydrochloric acid, is used, a hermetically sealed acid container is preferably used to prevent fuming and corrosion. A closed container is also preferably provided for the carbonate and powdered metal to insure against undesired reaction should the acid container be cracked or leakage occur.

105

Centrally arranged on the cover 16 is an opening 50 through which extends a slideable plunger 51. A stuffing box is formed about the plunger to prevent leakage. This comprises an upstanding threaded flange 52 carried by the cover receiving a screw cap 53 to compress within the packing gland suitable packing 54. The lower end of the plunger rod 51 which extends through the cover 16 to the interior of the extinguisher is provided with an interior bore 55 adapted to loosely receive therein an upper extension 56 of smaller diameter of a second plunger rod 57. This plunger rod 57 slidably extends through an opening 58 in the stopper 45, the lower end of the plunger rod being pointed as at 59 and terminating short of the bottom of the container 44. The inner end of the plunger rod 51 is preferably provided with exterior screw threads 60 adapted to receive thereon a nut 61 to prevent the plunger rod 51 from be- 110
115
120
125
130

ing withdrawn from the extinguisher. The rod 51 in its normal position extends above the upper surface of the handle 17 and is provided with an operating button 62.

5 To permit the gaseous pressure to be communicated from within the tube 30 to the spaced within the outer container 10, a valve controlled passage 63 is formed within the supporting rod 35. As shown, the upper end 10 of the passage 63 opens by a plurality of radial ports 64 into the space within the tube 30 adjacent the bottom thereof, and the lower end of the passage 63 opens by a plurality of radial ports 65 into the space within the outer container 10 adjacent the lower end thereof. The passage 63 is provided with a valve seat 66 which normally receives in sealing engagement a spring pressed valve 67. A spring 68 bears respectively against the bottom 20 of the rod 35 and a collar 69 on the valve stem 70 which is slidably mounted in the bottom of the rod 35.

This construction prevents the fire extinguishing liquid within the outer container 25 from passing into the tube 30. When the extinguisher is inverted, the outlet ports 65 of the passage 63 are then disposed above the liquid level within the outer container. The gas pressure produced within the tube 30 by 30 reaction of the generating materials overcomes the tension of the spring 68 to open the valve 67, permitting the gas to pass through the passage 63 into the space within the outer container to expel the fire extinguishing liquid.

In operation, the extinguisher is inverted and bumped down upon the floor or other 35 convenient surface, driving the plunger rods 51 and 57 inwardly. The bottom 75 of the container 44, and the inverted bottom 76 of the container 41 are formed of a thin frangible material, such as glass, whereby the pointed end 59 of the plunger breaks the two frangible containers permitting the acid 40 within the container 41 to flow down into contact with the dry gas generating material within the container 44. Even at extremely 45 low temperatures the acid reacts rapidly with the powdered metal generating sufficient heat 50 to warm up the surrounding materials of the charge to a temperature such that effective reaction between the carbonate and the acid with the evolution of CO_2 gas results. This gas passes through the valve controlled passage 55 63 into the upper end of the now inverted container 10 to produce an expelling pressure therein.

In Figs. 2 and 3 is shown a somewhat modified form of inner tube and valve controlled 60 pressure discharge. This comprises a sheet metal tube 30' which may be suspended from the cover as shown in Fig. 1. The tube is provided with a cast metal bottom 80 having a threaded opening 81 adapted to receive an 65 upstanding supporting rod 35' which sup-

ports the cup shaped acid container 37'. The casting 80 is also provided with an opening 82 receiving therein a hollow tube 83, the lower end of which is formed with a valve seat 84, with which cooperates a valve 85 70 carried by one arm of a lever 86. Rigidly fastened to the interior wall of the tube 30' below the casting 80 is a casting 87 which is bifurcated to provide two spaced extending arms indicated at 88 and 89. The casting 75 87 provides a lower support as indicated at 90 for the tube 83. A pin 91 is mounted between the arms 88 and 89, and the lever 86 is pivotally mounted upon this pin. The other arm of the lever 86 carries a lead weight 80 92, which in the upright position of the extinguisher urges the valve 85 into sealing engagement with the valve seat 84 to prevent the ingress of liquid into the tube 30'. The ends of the arms 88 and 89 are curved downwardly as indicated at 93 to properly guide the rocking movement of the lever 86.

In operation, when the extinguisher is inverted, the weight 92 rocks the lever by the force of gravity about the pivot pin 91 to remove the valve 85 from its seat 84, thereby permitting the gas pressure generated within the tube 32' to pass freely into the space within the outer container.

While the forms of invention herein described constitute preferred embodiments thereof, it is to be understood that the invention is not to be limited to these precise forms, and that changes may be made therein without departing from the scope of the 95 invention which is defined in the appended 100 claims.

What is claimed is:

1. In a fire extinguisher charge, a normally separated gas generating portion comprising a gas forming material and a metal.

2. In a fire extinguisher charge, a normally separated gas generating portion comprising a carbonate bearing material mixed with a finely divided metal.

3. In a fire extinguisher charge, a normally separated gas generating portion comprising a carbonate bearing material mixed with powdered magnesium.

4. A fire extinguisher charge comprising as normally separated portions, an acid liquid, and a metal adapted to react exothermically therewith.

5. A fire extinguisher charge comprising as normally separated gas generating portions, an acid liquid, and a gas forming material adapted to react at normal temperatures with said acid liquid, mixed with a metal adapted to react exothermically with the acid liquid to generate heat to promote the reaction of the said gas forming material with the acid liquid at temperatures below said normal temperatures.

6. A fire extinguisher charge comprising an acid, a carbonate bearing material, and a

finely divided metal adapted to react exothermically with the acid.

7. A fire extinguisher charge comprising as normally separated portions, an acid, and
5 a dry carbonate bearing material mixed with powdered magnesium.

8. A fire extinguisher charge comprising as normally separated portions, hydrochloric acid, and a dry carbonate bearing material
10 mixed with powdered magnesium.

9. A fire extinguisher charge comprising as normally separated portions, a fire extinguishing liquid which is non-freezing at low temperatures, an acid liquid which is also
15 non-freezing at low temperatures, and a gas generating material mixed with a finely divided metal.

10. A fire extinguisher charge comprising as normally separated portions, a fire extinguishing liquid which is non-freezing at low temperatures, an acid which is also non-freezing at such low temperatures, and a dry carbonate bearing material mixed with powdered magnesium.

25 In testimony whereof I hereto affix my signature.

ROSCOE C. IDDINGS.
